UNITED STATES PATENT OFFICE.

LOUIS GOHLKE, OF GRAND RAPIDS, MICHIGAN.

DESIGN FOR A CARPET-SWEEPER CASING.

SPECIFICATION forming part of Design No. 24,055, dated February 19, 1895.

Application filed September 14, 1894. Serial No. 523,043. Term of patent 7 years.

To all whom it may concern:

Be it known that I, LOUIS GOHLKE, a citizen of the United States, residing at Grand Rapids, in the county of Kent and State of Michigan, have invented a certain new and original Design for a Carpet-Sweeper Casing, of which the following is a specification.

This design relates to a carpet sweeper casing and the distinctive features thereof are the longitudinally rectilinear top of the case, having a triangular carved escutcheon plate, and the braid-like band surrounding the case, as more fully illustrated in the accompanying drawings, in which—

Figure 1 is a plan view of a carpet sweeper casing embodying said design; and Fig. 2 an end view of the same.

Like letters refer to like parts in both of the figures.

A represents the top of the case, which is 20 longitudinally rectilinear and transversely curved, having a convex and raised middle portion and concave and lower side portions, substantially as shown, and provided near one end with a substantially triangular escutcheon plate B, having two carved sides.

C is a band having the form and appearance of woven or braided fabric and surrounding the case in a horizontal plane.

What I claim is— 30

The design for a carpet sweeper casing substantially as shown and described.

In testimony whereof I affix my signature in presence of two witnesses.

LOUIS GOHLKE.
